SUBMERSIBLE WELL PUMP LUBRICATING SYSTEM

James M. Hait, Los Angeles, Calif., assignor to
Food Machinery Corporation, a corporation of
Delaware

Application April 18, 1938, Serial No. 202,603

8 Claims. (Cl. 184—6)

This invention relates generally to submersible well turbine pumps such as are used in pumping water wells for domestic or industrial purposes. More particularly, this invention relates to methods of and apparatus for lubricating the motor of a submersible well pump and for returning lubricant to the surface without permitting its escape into the well liquid.

The invention as disclosed in this application is particularly designed for use in combination with or as a part of a submersible well pump wherein the motor is located below the impellers of the pump, however, the invention is also applicable to submersible pumps wherein the motor is above the impellers, such as disclosed in my co-pending application for patent on a submersible pump, filed of even date herewith.

The difficulties with the present submersible pumps are that they do not provide for the proper lubrication of the submerged motor. Some pumps provide for supplying lubricant to the motor but do not make provision for preventing contamination of the well liquid by leakage of the lubricant from the motor. As far as I am aware, no positive means has been provided for repelling the entrance of the well liquid into the motor housing except such constructions as employ a mercury seal.

It is a primary object of this invention to provide a new and improved submersible well pump with means associated therewith for supplying lubricant to the motor and for preventing escape of the lubricant into the well liquid.

It is also an object of this invention to provide a method of lubricating and positively repelling the entrance of well liquid into the motor housing by the use of lubricant. To accomplish this, lubricant is supplied to the motor housing at sufficient pressure to accomplish the purpose desired and to assure positive flow of lubricant from the motor housing outwardly. It is also an object to utilize pressure operable motor control means adapted to stop the motor when the pressure in the motor housing drops below a safe amount relative to that pressure existent outside of the motor.

It is a further object of this invention to incorporate as part of the submersible well pump assembly a thrust bearing seal for controlling the escape of lubricant from the motor housing.

It is a still further object of this invention to provide a chamber between the point at which lubricant may escape from the motor housing and the well liquid for the entrapment of lubricant escaping from the motor housing. It is also

an object to provide means in this chamber to prevent the lubricant from reaching a point where it might escape into the well liquid.

It is a further object of this invention to 5 trap lubricant which escapes from the motor and to provide for the substantial separation of the lubricant from any well liquid with which it may have become associated after it has escaped from the motor. It is also an object of this invention 10 to automatically return the separated lubricant to the surface of the ground.

These and other objects will be apparent from the drawings and the following description thereof. Referring to the drawings, which are for 15 illustrative purposes only,

Fig. 1 is a sectional elevation of a submersible well pump including the apparatus of this invention for lubricating the motor of the pump.

Fig. 2 is an enlarged fragmentary sectional 20 elevation of the thrust bearing seal located at the upper end of the motor housing and shown in Fig. 1.

Fig. 3 is a sectional elevation of the valve used in the accumulator and separator apparatus.

Fig. 4 is a sectional elevation of a form of 25 lubricant deflector applicable for use in the entrapment chamber of Fig. 1.

Fig. 5 is a sectional elevation of another form of lubricant deflector applicable for use in the 30 entrapment chamber of Fig. 1.

Fig. 6 is a diagrammatic view illustrating the 35 lubrication system.

More particularly describing the invention, reference numeral 11 indicates a delivery pipe 35 which is supported at the surface of the ground and serves as a conduit for the pumped liquid. At the lower end of the delivery pipe is a pump bowl 12 which houses an impeller (not shown). Reference numeral 13 indicates a suction manifold, the lower end of which has attached thereto 40 in any suitable manner a casing 14. This casing has a partition wall 15 which divides it into an upper portion 16 having perforations 16' which form a strainer inlet for the well liquid. The lower portion 17 of the casing, together with the 45 partition member 15 and the upper portion of the motor housing, later to be described, form what will be termed an entrapment chamber 18.

Reference numeral 19 generally indicates an 50 electric motor which is enclosed by a motor housing 20 comprising a lower section 21 and an upper section 22 which are secured together in any suitable manner so that the joint will be fluid tight. A motor shaft 23 is provided which is supported by ball bearings generally indicated

by reference numerals 24 and 25. The shaft carries a rotor 26 which rotates within the stator element 27. The motor shaft 23 extends through the motor housing, a thrust bearing seal generally indicated by reference numeral 30, and which will subsequently be described in detail, being provided in the region of the place where the shaft extends through the housing. The motor shaft 23 is connected to an impeller shaft 32 through the medium of two universal joints, generally indicated by reference numerals 33 and 34 and a short coupling shaft 35 between the aforementioned joints. The impeller shaft 32 carries the impeller, not shown, but which is located within the bowl 12.

The use of the universal joints between the impeller and the motor serves to eliminate the transmission to the motor of any vibration caused by wearing of the pump bowl, bearings, impeller, or other parts. The construction thus serves to 20 entirely isolate the impeller shaft from the motor shaft, with respect to any vibration set up in the impeller shaft, and thereby greatly increase the life of the motor.

For the purpose of lubricating the motor, there is provided a lubricant supply pipe 38 which leads from a suitable source of lubricant, preferably located in the region of the surface of the ground. The lubricant supply pipe is provided with a pressure regulating valve 39, shown diagrammatically. This valve is designed to prevent excessive pressure of lubricant within the motor, and accordingly should be adjustable so that it may be set for different pressures, depending upon the particular installation. The 35 greater the pressure of the well liquid in the region of the motor housing, the correspondingly greater lubricant pressure will be required in the motor housing.

It is an object of this invention to provide for the lubrication of the motor and also to provide for the positive prevention of entrance of well liquid into the motor housing by repelling entrance of such liquid by causing positive flow of lubricant from the motor housing outwardly thereof at the only point where the well liquid might enter the housing. To accomplish this it is necessary to feed the lubricant to the motor at a pressure in excess of the pressure of the well liquid in the region where the well liquid might enter the motor housing. In most installations the column of lubricant in the lubricant supply pipe 38, which would necessarily lead from the lubricant supply at the surface of the ground, would provide sufficient head to provide the necessary pressure within the motor. It is contemplated, however, that in some installations it may be necessary to include a lubricant pump between the source of supply of lubricant and the motor for the purpose of providing the necessary pressure and this pump has been included in the diagram of the lubricating system shown in Fig. 6, and later to be described.

Lubricant escapes from the motor housing through a thrust bearing seal, generally indicated by reference numeral 30, into what will be termed an entrapment chamber 18. A sleeve bearing 42 mounted on the upper end of the upper section 22 of the motor housing by means of suitable bolts 43 causes the escaping lubricant to follow the shaft 23 a considerable distance into entrapment chamber 18 before it can escape into the outer portions of the entrapment chamber. The details in the construction of 75

the thrust bearing seal 30 are best illustrated in Fig. 2 and accordingly, reference is hereby made thereto.

In the upper portion of the upper section 22 of the motor housing is formed an annular seat 45 designed to accommodate the outer race 46 of a double row ball bearing, generally indicated by reference numeral 47. This ball bearing is pre-loaded and is designed to support the thrust load of a rotating sealing sleeve 48 which bears against the end of the inner race 49 of the bearing. The sealing sleeve 48 is provided with a recess 50 designed to accommodate compressible packing members 51. The packing is compressed 15 into sealing engagement with the shaft and the sleeve by means of a compression spring 52 located between a slidable collar 53 and a collar 54 which is rigidly mounted on the shaft by means of a set screw 55. Other means of sealing the shaft and sleeve may be used, however. Pressure of liquid in the chamber 58 serves to further compress the packing 51 and to increase the end thrust of the sealing sleeve 48 against the inner race 49 of the bearing 47.

The bearing sleeve 42 has a machined inner end face 42' so that a precision fit may be achieved between the stationary inner end face 42' of the sleeve 42 and the sealing end face 48' of the sleeve 48. A portion of the sealing end face 48' of the sleeve 48 bears upon and is supported by the inner race 49 of the bearing. The bearing is pre-loaded so that precision fit is secured between the sealing faces 42'-48' which is virtually a metal to metal fit, the surfaces being separated only sufficiently to accommodate a very thin oil film. The fact that the ball bearing is pre-loaded to take care of the thrust load of the sealing sleeve 48 prevents wear of the sealing faces 42'-48' inasmuch as, regardless of the pressure in the chamber 58, the sealing faces can never be forced into engagement.

With the construction just outlined, the lubricant under pressure in the motor housing escapes from the chamber 58 gradually through the ball bearing 47, the lubricant passing between the inner and outer races, and over the top of the inner race and downwardly between the inner race and the bearing sleeve 42 to the region of the seal formed by the surfaces 42'-48' and then escapes upwardly through the bearing sleeve 42 into the entrapment chamber 18, as previously stated.

To prevent escape of the lubricant into the well liquid, the entrapment chamber 18, above referred to, is provided. The upper portion of this chamber, formed by the partition wall 15, is provided with a depending sleeve portion 60 which accommodates a bearing 61. Between the lower end of the bearing 61 and the upper end of the bearing sleeve 42 there is positioned suitable lubricant deflecting means, generally indicated by reference numeral 62. This oil deflecting means may take several forms, and is provided for the purpose of preventing the escaping lubricant issuing from the upper end of bearing sleeve 42 from escaping outwardly through bearing 61 and into the well liquid.

In Fig. 1 one form of oil deflector has been shown as comprising a double-aproned member 63 which is secured to the shaft and rotates therewith. Such member is effective to prevent lubricant gaining access to the lower end of bearing 61 and is effective to cause lubricant to accumulate in the upper portion of the entrapment chamber at a point above the lower end of the bearing 61.

A distinct advantage of the downwardly projecting skirt 63' lies in the fact that as oil issues from the motor assembly it will rise through the clearance inside of sleeve 42 and before escaping to the entrapment chamber it must pass downwardly out, around the upward projecting section of the sleeve 42, and in so doing creates an oil seal serving the purpose of preventing water from ingressing into the motor assembly when the pump is not in operation, or when, as might occur during non-operative periods, the pressure in the motor assembly may be below that which would exist during operation. For instance, if this downwardly projecting sleeve did not extend below the upward projecting sleeve 42, if the motor assembly should stand idle for a period of months, the pressure within could not be maintained in excess of that outside to cause leakage, and water might, by virtue of the difference in specific gravity, seep in through the seal.

In Figures 4 and 5 there are illustrated two other forms of oil deflectors. A small impeller 65 may be located at the lower end of the bearing 61 mounted on the shaft. This impeller would serve to create a slight decrease in pressure in the region of the lower end of bearing 61 and serve to slightly increase the pressure in the outer regions of the entrapment chamber. With this construction lubricant cannot enter the lower end of bearing 61.

Fig. 5 illustrates the use of a disc 66 which might be mounted on the shaft at the lower end of the bearing 61 and which would be effective to deflect lubricant flowing upwardly in the chamber around sleeve 60 so that the lubricant would accumulate in the upper portion of the entrapment chamber above the lower end of bearing 61.

Leading from the upper end of the entrapment chamber 18 there is provided a conduit 68 which extends upwardly into the lower portion of a lubricant accumulator and separator apparatus, generally indicated by reference numeral 70. This apparatus is of the type disclosed and claimed in my co-pending application for patent on Automatic oil return system for turbine pumps, Serial No. 133,372.

The accumulator and separator apparatus generally comprises a casing 71 surrounding the delivery pipe 11 and provided with a partition 72 whereby a closed upper chamber 73 and a lower chamber 74, which is open to the well liquid, are provided. The upper chamber 73 is in communication with the interior of the delivery pipe through the medium of a port 75 which is located in the lower portion of the upper chamber. Leading from the upper portion of the upper chamber is a lubricant return conduit 76 for returning lubricant from the accumulator and separator apparatus to the surface of the ground. Mounted in the partition 72 is a normally open valve 77 which is closable by pressure in the upper chamber 73.

In the operation of the accumulator and separator apparatus, lubricant enters the lower chamber 74 by means of conduit 68 and accumulates below the partition 72 during the operation of the pump. Inasmuch as the pressure in the chamber 73 exceeds that in chamber 74 by reason of the communicating port 75, the valve 77 remains closed. When the pump is stopped, the valve, which is spring loaded, opens and permits escape of the lubricant into the upper chamber where it accumulates in the upper portion thereof and conduit 76. When the pump is again started, 75

the pressure in the upper chamber forces the lubricant to the surface of the ground.

One form of valve which has been found suitable for use in this apparatus is shown in Fig. 3 and comprises generally a valve body 80 centrally bored at 81, the bore terminating in a valve seat 82. Above the valve seat the valve body 80 is hollow and provided with the openings 83. Mounted in the top of the valve body is a cap member 84 centrally apertured at 85 and having a depending sleeve portion 86 to accommodate a valve stem 87 which has a metallic conical head 88 adapted to fit valve seat 82. The valve is spring loaded and includes a compression spring 89 between cap member 84 and the washer 90 which is held in place by the nut 91. Adjacent the head 88 is an oil resisting resilient sleeve 92 which swells into place when the valve is in contact with the seat. In the event abrasives or other material should prevent the metallic valve from fitting tightly, the pressure above the resilient ring will compress it into engagement with the inner surface of the valve body and seal any leakage which might take place past the metallic surface of the valve.

It is, of course, within the scope of the invention to eliminate the accumulator and separator apparatus and return the lubricant directly to the surface of the ground.

In the operation of the lubricating system, a lubricant supply (see Fig. 6) is provided at the surface of the ground. This is connected to the pump by means of the lubricant supply pipe 38. Positioned between the two elements is the pressure regulator valve 39 above referred to, designed to prevent excessive pressure in the motor housing in order to avoid excessive leakage. In some installations it may be necessary to provide a lubricant pump in order to secure the necessary pressure of lubricant in the pump housing, and this is shown in the diagram of Fig. 6. Suitable valves 95 and 96 are provided for controlling the flow of lubricant and for the optional use of the lubricant pump. It is to be understood that not all installations require the use of a lubricant pump and the lubricant pump has been included in Fig. 6 as an optional element.

Lubricant passing down the lubricant supply pipe 38 enters the motor housing at the predetermined pressure, which is in excess of the pressure in the region of the strainer 16. Lubricant flows outwardly through the thrust bearing seal 30 and into the entrapment chamber 18 where it accumulates in the upper portion thereof and is prevented from escaping into the well liquid through bearing 61 by lubricant deflectors 62 which may take various forms as herein above described.

Some well liquid may enter the chamber 18 through bearing 61 and consequently lubricant in chamber 18 will become mixed with water or well liquid to a certain extent. Positive flow of lubricant upwardly through bearing sleeve 42 prevents entrance of any well liquid into the motor housing, however. Since the lubricant in chamber 18 may become mixed with the well liquid, the liquid which flows upwardly in conduit 68 may be a mixture of lubricant and well liquid, especially after the pump has been in operation for some period of time.

Liquid flowing upwardly in conduit 68 is discharged into lower chamber 74 of the accumulator and separator apparatus 70. The lubricant tends to separate from the well liquid in this chamber and accumulate beneath partition

72 during operation of the pump. When the pump is stopped the valve 77 opens and permits the lubricant to escape into the upper chamber 73 where it rises to the top. Upon restarting of the pump, the lubricant is forced to the surface through lubricant return pipe 16 which may lead to the lubricant supply.

The accumulator and separator 70, to function properly, must necessarily have its lower end substantially submerged in the well liquid during operation, and the upper portion thereof, 73, must be submerged during non-operating periods in order to float the oil from the lower portion of accumulator 74, and the lower end of the casing should at all times be below the surface of the well liquid.

Extending from a suitable source of electricity is an electric cable 98 which is supported on the conduit 38 by means of suitable clamps 99. This cable connects the motor to the source of electricity and to suitable control means and also connects in circuit with those elements a pressure operable electric control device 100. This device should preferably be of a type operable by the differential of pressure existent within and without the motor housing and for this purpose there is provided a port 101 in the motor housing to establish communication between the interior of the device and the exterior of the motor housing. The control device is designed to stop the motor when the pressure in the motor housing drops below a safe minimum relative to the pressure existent externally of the motor housing.

Although this invention discloses means for feeding lubricant to a submersible motor and for returning that lubricant to the source of supply, it is within the scope of this invention to feed lubricant to the motor under pressure and to permit escape of that lubricant into the well liquid at a point above the suction intake of the pump. Thus, lubricant might be permitted to escape at the upper end of conduit 68 directly into the well liquid instead of into an accumulator and separator structure from whence means is provided for returning lubricant to the surface of the ground. In other words, the invention also contemplates the lubrication of a submerged motor by use of a lubricant feed to the motor under pressure with means for bypassing such lubricant as it escapes from the motor past the point at which the well liquid enters the pump so that lubricant will not contaminate the well liquid in the region where it enters the pump.

I claim as my invention:

1. In apparatus of the type described, the combination of: a submersible motor enclosed by a housing having a shaft extending through said housing; casing means forming an entrapment chamber adjacent said motor housing surrounding said shaft; means for delivering lubricant to said motor under pressure; a thrust bearing seal surrounding said shaft in the region where the shaft passes through the motor housing, said seal being adapted to permit a limited flow of lubricant from the motor housing into said entrapment chamber; and means for conducting lubricant from said entrapment chamber to a desired point.

2. In apparatus of the type described, the combination of: a submersible motor enclosed by a housing having a shaft extending through said housing; casing means forming an entrapment chamber adjacent said motor housing surround-

ing said shaft, the upper portion of said casing means forming a depending sleeve extending a substantial distance into said entrapment chamber; a bearing interposed between said sleeve and said shaft; a lubricant deflector mounted on said shaft below said sleeve for preventing lubricant from escaping through said bearing; means for delivering lubricant to said motor under pressure; means surrounding said shaft in the region where the shaft passes through the motor housing and into the entrapment chamber providing a restricted passage of predetermined dimensions; and means for conducting lubricant from said entrapment chamber to the surface of the ground.

3. In apparatus of the type described, the combination of: a submersible motor enclosed by a housing having a shaft extending through said housing; casing means forming an entrapment chamber adjacent said motor housing surrounding said shaft, the upper portion of said casing means forming a depending sleeve extending a substantial distance into said entrapment chamber; a bearing interposed between said sleeve and said shaft; means on said shaft for reducing the pressure at the lower end of said bearing and for causing flow of liquid outwardly from that region to the outer portions of the entrapment chamber; means for delivering lubricant to said motor under pressure; means surrounding said shaft in the region where the shaft passes through the motor housing and into the entrapment chamber for permitting a limited flow of lubricant from said motor housing into said entrapment chamber; and means for conducting lubricant from said entrapment chamber to the surface of the ground.

4. In a submersible motor adapted for operation in a well, the combination of: housing means forming a motor chamber having an opening at its upper end; a motor in said chamber; said motor chamber being filled with oil; a shaft extending from said chamber out through said opening; casing means forming an entrapment chamber surrounding said shaft immediately above said motor chamber, said casing means forming a depending sleeve extending a substantial distance into said entrapment chamber; a bearing in said sleeve journaling said shaft; means for supplying said motor chamber with oil at a pressure sufficient to cause said oil to flow from said motor chamber into said entrapment chamber; and means for conducting liquid from the upper end of said entrapment chamber from a point above the lower end of said sleeve to a point out of the well.

5. In a submersible motor adapted for operation in a well, the combination of: housing means for forming a motor chamber having an opening at its upper end; a motor in said chamber; said chamber being filled with oil; a shaft extending from said chamber out through said opening; casing means forming an entrapment chamber surrounding said shaft immediately above said motor chamber, said casing means forming a depending sleeve extending a substantial distance into said entrapment chamber; a bearing in said sleeve journaling said shaft; means forming a sleeve surrounding said shaft in the region of the opening between said motor chamber and entrapment chamber extending upwardly into said entrapment chamber; an oil deflector means comprising a member mounted on said shaft between said sleeves and having an upper apron extending over said depending sleeve and a

ower apron extending over said upwardly extending sleeve; means for supplying said motor chamber with oil at a pressure sufficient to cause said oil to flow from said motor chamber into said entrapment chamber; and means for conducting liquid from the upper end of said entrapment chamber from a point above the lower end of said depending sleeve to a point out of the well.

6. Oil entrapment means for use in combination with a chamber from which a shaft extends and from which oil is extruded comprising: housing means forming an entrapment chamber surrounding said shaft immediately above said chamber, said housing means forming a depending sleeve extending a substantial distance into said entrapment chamber surrounding said shaft; means forming an upwardly extending sleeve round said shaft; oil deflector means mounted on said shaft intermediate the two sleeves; and means for conducting entrapped oil from said entrapment chamber, the inlet of said conducting means being located at a point above the lower end of the depending sleeve.

7. Oil entrapment means for use in combination with a chamber from which a shaft extends and from which oil is extruded comprising: housing means forming an entrapment chamber surrounding said shaft immediately above said first

mentioned chamber, said housing means having an opening in its upper end surrounded by a sleeve projecting downwardly from the upper wall of said housing and through which said shaft extends, a portion of said entrapment chamber being located above the lower end of said sleeve; and means for conducting entrapped oil from said entrapment chamber, the inlet of said conducting means being located above the lower end of said sleeve.

8. Oil entrapment means for use in combination with a chamber from which a shaft extends and from which oil is extruded comprising: housing means forming an entrapment chamber surrounding said shaft immediately above said first mentioned chamber, said housing means having an opening in its upper end surrounded by a sleeve projecting downwardly from the upper wall of said housing and through which said shaft extends, a portion of said entrapment chamber being located above the lower end of said sleeve; an oil deflector mounted on said shaft below said sleeve and having a portion surrounding said sleeve; and means for conducting entrapped oil from said entrapment chamber, the inlet of said conducting means being located above the lower end of said sleeve.

JAMES M. HAIT.
